AERIAL FLARE

John F. Cavanagh, Providence, R. I., assignor to
 Kenney Manufacturing Company, Cranston,
 R. I., a corporation of Rhode Island

Application September 17, 1942, Serial No. 458,677

14 Claims. (Cl. 102—35.6)

Aerial flares of the type embodying a candle and a parachute with some form of sleeve or pilot for the latter within a case, call for means for effecting a chain of coordinated events between the release of the flare from a plane and its ignited state.

These events may be briefly described as the withdrawal of the parachute pilot, the removal of the inclosing case to release the parachute, and finally the ignition of the candle. It is imperative that the foregoing events be effected with certainty at predetermined intervals.

Practice demands that the parachute shall be stabilized and the candle ignited at a predetermined point, usually approximately three thousand feet from the ground, and inasmuch as flares are released at various heights much above this, it is obvious that accurate and dependable timing means for releasing the parachute and effecting ignition must be provided if satisfactory operation is to be attained.

Heretofore pyrotechnic means involving various time factors and explosive force have been largely utilized in attempts to bring about the foregoing events.

The broad object of the present invention is to provide mechanical means for effecting the chain of events now brought about by pyrotechnic means.

By eliminating the use of pyrotechnic means for effecting release of the parachute and ignition of the candle at a predetermined point in the drop of the flare, and substituting therefor a mechanically timed release which is simple in structure and dependable in operation, I avoid the danger of the flare failing to function at the proper time, due to deterioration of the pyrotechnics, miscalculation in respect to the proper kind, quality, or volume of pyrotechnics used, and like factors making for defective or improper operation.

Another object is to provide the mechanical means with simple and dependable timing functions.

An outstanding advantage of the mechanical means for ejecting the case and effecting ignition under the control of a calibrated spring motor resides in the fact that these functions may be carefully checked to the extent of actual operation before final assembling in the flare. This advantage cannot be attained where pyrotechnic materials are depended upon in any manner to time operations or effect the removal of the case.

Another object is to provide means for adjust-

ing the timing function by remote control from a central point in the plane.

By constructing this mechanically timed release so that it may be adjusted by remote control, that is to say, by the pilot in the plane at the time he wishes to launch the flare having regard to such factors as altitude, visibility and the like, I enable the pilot to overcome the ground-set and frequently inappropriate timing adjustment which was given the flare prior to flight and which may no longer be appropriate for the conditions existing at the time the flare is actually launched.

Another object is to provide an improved shade for the candle.

By constructing the shade for the candle as a plurality of fire-resistant sections separably attached to the candle so as to successively drop off as the candle is progressively consumed, I avoid the necessity of using a single foldable shade of consumable material which not only must be withdrawn from the case and accurately unfolded while the flare is dropping but when unfolded must always occupy a position sufficiently high above the ignited candle as not to be affected thereby. Where a single foldable shade is used, the shade must of necessity be supported at the top of the candle, and to make such shade effective when ignition starts, the shade must necessarily be of a length which tends to cause it to turn inside out as the flare falls.

Other objects and advantages of my invention will be apparent as the description proceeds.

As a result of these various improvements, my flare is simpler and cheaper to construct than flares of comparable type now in service and is far more dependable in operation.

In the accompanying drawings I have disclosed a preferred embodiment of my invention which well illustrates the principles involved. It is recognized, of course, that the invention is susceptible of various changes as to the form, size, proportions and construction and arrangement of its component parts, and all such changes are to be regarded as equivalents if they function in substantially the same manner to accomplish substantially the same purpose.

For convenience of illustration, I have omitted from such drawings those features of the flare which form no part of my present invention but are standard equipment in flares of the parachute-supported type, such as the parachute itself, the arming wire-hangwire assembly, and like conventional parts.

Referring to the drawings:

Fig. 1 is a fragmentary sectional view of a flare in accordance with my invention, showing the various components in the position they normally occupy within the case before the timed mechanical release mechanism operates.

Fig. 2 is a similar view, foreshortened, showing the position of the parts after the mechanical release mechanism has operated to force the case away from the case contents.

Fig. 3 is an enlarged fragmentary sectional view 10 at the nose of the flare particularly showing the timed mechanical release mechanism.

Fig. 4 is a sectional view on the line 4—4 of Fig. 3 looking in the direction of the arrows.

Fig. 5 is a sectional view on the line 5—5 of 15 Fig. 3 looking in the direction of the arrows.

Fig. 6 is an end view, as seen from the left, of the timing sleeve shown in Fig. 7.

Fig. 7 is a side elevation of said sleeve.

Fig. 8 is a section on the line 8—8 of Fig. 7.

Fig. 8^a is a perspective view of said sleeve, and Fig. 9 is an end view of the nose of the flare showing the time adjusting means.

Referring to Figs. 1 and 2, 10 is a conventional sheet metal case provided at its tail end with several rigid stabilizing vanes or fins 11.

In the flight of the flare, the rounded or nose portion 10' of the case is downward and hence may be referred to as the bottom, while the end carrying the fins 11 is upward and hence may be considered as the top. The upper end of the casing 10 is adapted to contain a conventional parachute and appurtenances (not shown).

Slidably supported within the lower end of case 10 is a tubular member 12 of suitable material adapted to retain a compressed illuminant composition 13, and having mounted on its exterior a sectional fire resistant shade 14. Each shade section 14 is separately attached as at 14' to member 12 and each shade section comprises an annular sleeve portion 14^a disposed about member 12 and a circumferential flange portion 14^b extending angularly downwardly with reference thereto. The angle of the flange is such as best to snade the ignited candle 13 when viewed from above and there is sufficient clearance between the edges of the flanges and the inside surface of the case wall to permit the case and candle to separate from each other after the candle has been ignited.

The candle 13 is ignited at and burns from its lower end. As the tubular container 12 is consumed, the shades 14 successively drop off one by one as consumption proceeds. While I have shown the several shade sections, as rigid with the candle, it is obvious that they might be foldable and of a diameter when expanded considerably greater than the diameter of the case.

The lower end of illuminant member 12 is fitted with a sheet metal closure 15, which serves as a mounting for the spring motor housing 16.

Referring to Fig. 3, studs 17 are riveted to closure 15 and serve to support motor housing 16 which consists of base plate 18, end plate 19, and spacer 20.

Mounted upon end plate 19 is a spring motor provided with a driving shaft 21 actuated by torsion spring 22. Rigidly mounted on shaft 21 is gear 23 to which one end of spring 22 is anchored, while the other end of said spring is anchored to gear plate 24 which in turn is loosely mounted upon driving shaft 21 and retained against platen 25.

Referring to Fig. 4, it will be seen that platen 25 serves as a mounting for pinion 26 meshing

5 with gear plate 24. The pinion shaft is squared as at 27 to receive a wrench or key for the purpose of winding driving spring 22. A pawl 28 engaging the teeth of gear plate 24 serves to lock the latter in any desired position with respect to the desired amount of tension to be imparted to driving shaft 21 by spring 22.

The inner end of driving shaft 21 is provided with a face plate covered with a coating of friction material 29 for a purpose about to be explained. Mounted between end plate 19 and platen 25 is a train of gears 24' leading from gear 23 to an escapement 30 as shown in Fig. 4. Pivoted upon platen 25 is a disk 31, carrying pin 32 adapted to engage the escapement 30 when disk 31 is turned into locking position. These parts have been omitted from Fig. 3 for the sake of clarity but are detailed in Fig. 4. A light cable 33 is attached to disk 31 and functions to unlock the escapement in a manner to be explained later.

Referring to Figs. 3 and 5, 34 is a stub shaft centrally attached to base plate 18 and spaced from but in alignment with driving shaft 21. Rotatably and slidably mounted upon stub shaft 34 is a sleeve 35 carrying a cam point 36, counterbalanced as at 36' (see Fig. 5). A friction washer 37 surrounding the inner end of stub shaft 34 and attached to base plate 18 serves to lock sleeve 35 in its stationary position.

A rock shaft 38 supported in brackets 39 attached to base plate 18 carries dog 39 for engagement with cam point 36 under the tension of spring 40. One end of shaft 38 is externally threaded to receive an adjustable collar 39^a for adjusting the distance of overlap of dog 39 with respect to cam point 36. Two arms 41 also carried by shaft 38 are attached at their outer ends to friction wires in igniters 42 seated in base plate 18 in proximity to the first fire composition 13' of illuminant container 12. Space has been provided between base plate 18 and first fire composition 13' for holding a highly inflammable composition 13^a, and suitable recesses 13^b are provided in first fire composition 13' to insure effective ignition of said first fire composition 13' when said igniters 42 are actuated.

50 Pivoted at 43' upon base plate 18 is trigger 43 normally held by spring 43^a under spring pressure against the side of case 10, as shown in Fig. 3. Pivoted with trigger 43 is a yoke comprising spaced arms 45 which engage sleeve 35 as at 45' (Fig. 5) for the purpose of sliding the latter axially from contact with friction washer 37 into contact with friction surface 29 on driving shaft 21. A projection 46 on said trigger normally engages a spring 47 on arms 45 and serves to hold sleeve 35 securely against the friction washer 37 on base plate 18. A dog 48 on trigger 43 is arranged to engage a pin 49 on arms 45 when said trigger is permitted to release through removal of case 10, thus snapping sleeve 35 outwardly into engagement with drive shaft 21.

55 Suitably mounted in the nose of case 10 is a spring seat 50 upon which a powerful compression spring 51 is seated and held in compression by spring retainer 52 through the functions of axially mounted locking members 55 and 62 about to be described. Projecting inwardly from spring seat 50 is a tubular member 53 provided with a lug 54. Positioned within said tubular member 70 is adjusting shaft 55 provided at its inner end with a lug 56 similar to lug 54.

A gland 50' in seat 50 serves the double purpose of sealing shaft 55 against moisture and imparting a degree of friction to shaft 55 as

safeguard against shock tending to turn it. A washer 57 of soft packing material is retained by the head of the gland as shown.

Mounted upon the outer end of shaft 55 is adjusting knob 58 (see Figs. 1 and 9) provided with an index pointer 59 adapted to register with dial 60 on seat 50. Knob 58 also carries a serrated member 61 arranged to press into washer 57 under operating conditions to be described later.

A timing sleeve 62, detailed in Figs. 6, 7, 8 and 8^a, is provided with a slotted head 63 and two spaced arcuate locking surfaces 64 and 65. Said sleeve is adapted to slip over tubular member 53 with its locking surfaces 64 and 65 normally engaged with and retained by lugs 54 and 56 respectively. The sleeve head 63 serves to hold spring retainer 52 against the thrust of spring 51 while a ball thrust bearing 62' positioned as shown reduces friction in operation. The cross slot 63' in head 63 engages a cross pin 21' in driving shaft 21 to provide the turning means. The ends of a curved key member 66 integral with case nose 10' positively engage and serve to so position spring seat 50 and end plate 19 as to insure predetermined timing relations between driving shaft 21 and timing sleeve 62. Spring seat 50 is slotted as at 50^a and end plate 19 is slotted as at 19' to receive the ends of key 66. When the release mechanism operates key 66 is withdrawn from slot 19' (see Fig. 2).

Reference to Figs. 7 and 8^a will show that arcuate locking surface 64 is comparatively short and serves to normally hold spring 51 in compression against a small amount of turning motion of timing sleeve 62 while arcuate surface 65 is long enough to permit a range of adjustment of its engaging lug 56, thus determining the portion of a revolution through which driving shaft 21 must turn before timing sleeve 62 releases spring 51. As shown in Fig. 3, however, there is a small amount of clearance between lug 56 and its corresponding locking surface 65 while timing sleeve 62 is normally locked against rotation by lug 54. This permits free angular adjustment of lug 56 through the function of knob 58 to fix the number of elapsed seconds between the start of driving shaft 21 and the release of spring 51. While I have shown two locking surfaces 64 and 65 and two lugs 54 and 56 as preferable construction, due to the fact that the thrust of the spring 51 is considerable and might exert an excessive amount of frictional resistance to the adjustment of lug 56, it is obvious that locking surface 64 and lug 54 might be omitted under some circumstances.

After timing sleeve 62 turns enough to disengage from stationary lug 54, the thrust of spring 51 is taken by adjustable lug 56, which causes shaft 55 to slide outwardly sufficiently to permit the serrations on member 61 to embed in the soft surface of washer 57 and thus lock shaft 55 against further angular movement until surface 65 functions to release spring 51. This means of timing the release of spring 51 permits remote control of timing functions through utilization of a flexible shaft 67 detachably connected to shaft 55 as shown in Fig. 3, and operable by the pilot in the plane when desired according to conditions existing at the time that the flare is to be launched, in which event, the plane can be equipped with a dial and pointer corresponding to that detailed in Fig. 9 for manipulation by the pilot.

It is common practice in flares of this type 75

to attach a parachute to the upper end of the illuminant holder and incorporate said parachute together with its shrouds in folds within the case immediately above the illuminant holder. This arrangement requires a pilot or sleeve, attached to the top of the parachute, to effect the unfolding of the latter at the moment of release, and said parachute pilot together with its shrouds is also folded and packed over the parachute.

10 The release of the parachute is effected by the removal of the metal case 10 during the course of the downward flight of the flare. A cord or cable commonly called a hang-wire leading from the parachute pilot to a hook on the plane is provided, and the comparatively light cord 33 is attached to the hang-wire for the purpose of starting the timing functions when the flare has left the plane.

Assuming that a flare has been assembled involving my improved mechanism, together with its parachute and pilot as just described, and that it has been mounted in the launching rack of the plane with the end of the hang-wire properly attached to the latter, the order of operations is as follows:

20 Practice has shown that a point approximately three thousand feet above the earth is most advantageous for starting the burning of the illuminant. In these premises the timing device must be so adjusted as to permit the flare to fall a vertical distance corresponding to the difference 30 between the point of release and three thousand feet before igniting.

25 If the height of the releasing point has been predetermined, this adjustment is ordinarily made before the plane leaves the ground, but in my improved mechanism, provision has been made for effecting this adjustment either in the hangar, or while the plane is in the air. If ground-set, 30 the adjustment is made by means of the hand-knob 58 and dial and pointer detailed in Fig. 9. If the adjustment is made during flight, the flexible shaft 67 is used. The number of elapsed seconds between the start of timing shaft 21 and the release of case 10 through the function of spring 51 is determined by the position of lug 56 with respect to surface 65 through adjustment of knob 58. The starting of timing shaft 21 is controlled by cord 33 attached to the flare hang-wire. Thus it will be seen that the spring motor is not started until the flare has fallen a distance corresponding to a predetermined length of hang-wire.

35 The flare is released in the usual way, and after it is free from danger of fouling the hang-wire, draws cord 33 releasing escapement 30 when said cord 33 severs. The hang-wire then withdraws the parachute pilot and by means in common practice severs its connection with the latter so that the flare falls toward its destination guided by the fins 11 on case 10 and the parachute pilot. When it has fallen to the three thousand foot height as determined by the timing adjustment, ejecting spring 51 is released, thus forcing case 10 away from the illuminant assembly 13 and its attached spring motor (see Fig. 2) so that said case and its spring 51 now fall free. In this action, the shaft 21 has been rotated by its clockwork through a sufficient portion of a revolution to cause the end of surface 65 to disengage from lug 56, thus releasing spring 51.

40 The removal of case 10 frees the parachute, and its pilot thereupon functions to draw it out into condition for inflation so as to check the

descent of the illuminant. The removal of case 10 likewise frees trigger 43 which functions to throw sleeve 35 into engagement with the friction surface 29 of driving shaft 21 so as to be slowly rotated thereby. After the required number of seconds to enable the freed parachute to stabilize, as determined by the relations of cam point 36 and dog 39, cam point 36 is rotated from beneath dog 39, permitting arms 41 to operate under the impulse of spring 40 to jerk the friction wires of igniters 42 and ignite the candle 13. It may be stated here that these igniters 42 with their friction wires are widely utilized and constitute satisfactory and dependable means for effecting ignition of the candle.

The act of jerking the igniter wires serves to ignite first fire composition 13' in proximity to said igniters, and the burning of the illuminant begins. The end of the illuminant casing supporting the motor housing 16 is immediately consumed and said housing drops free while the illuminant assembly floats downward supported by the parachute. As consumption of the illuminant proceeds, shades 14 are released one by one.

Various modifications in construction and arrangement may obviously be resorted to within the spirit and scope of my invention as defined by the appended claims.

What I therefore claim as desire to secure by Letters Patent is:

1. An aerial flare of the parachute-supported type, comprising a case adapted to house an illuminant and its supporting parachute, a mechanical release mechanism for stripping the case from the illuminant and its supporting parachute at a predetermined point in the fall of the flare, a timing mechanism for controlling said release mechanism including a spring motor and a driving shaft, a normally-locked escapement in control of said motor, unlocking means for said escapement adapted to be actuated substantially coincidentally with the launching of the flare from the aircraft, and auxiliary timing means for igniting the illuminant, said auxiliary timing means being actuated by the withdrawal of the flare case from the illuminant and its supporting parachute and when actuated being moved into coupled engagement with said driving shaft.

2. The flare of claim 1, said auxiliary timing means including a lock for positively holding the same in a normally inoperative position.

3. The flare of claim 1, said auxiliary timing means including a rotatably and slidably mounted sleeve alined with but spaced from said driving shaft and having a cam, and there being a spring-tensioned rock shaft having a dog disposed for coaction with said cam whereby after a predetermined degree of rotation of said sleeve said cam will release said rock shaft, and said rock shaft carrying ignition effecting devices for igniting said illuminant when said rock shaft is released.

4. The flare of claim 1 and a spring-tensioned trigger normally retained against actuation by contact with the wall of the case, a spring-tensioned yoke pivoted to said trigger and engaging said auxiliary timing means for moving the same into coupled engagement with said driving shaft when said trigger is released by withdrawal of said case from its holding engagement therewith.

5. An aerial flare of the parachute-supported type, comprising a case adapted to house an illuminant assembly and its supporting parachute,

5 a mechanical release mechanism for stripping the case from the illuminant assembly and its supporting parachute at a predetermined point in the fall of the flare, said mechanical release mechanism including a spring seat and a spring retainer mounted in spaced relation to each other within the nose of the flare case and a compression spring reactive between said seat and retainer, a timing mechanism including a spring motor and a driving shaft mounted in the flare case above said release mechanism and attached to the illuminant assembly, and quick-detachable means normally connecting said driving shaft with said release mechanism but releasable after the driving shaft has turned a timed distance thereby to release said spring so that it may expand and cause the case to be stripped from the illuminant assembly.

6. The flare of claim 5, and means adjustable at a point remote from the flare for changing the setting given said timing mechanism.

7. The flare of claim 5, and an angularly adjustable setting shaft spaced from and alined with said driving shaft and having a locking lug, and a timing sleeve keyed to said driving shaft and having a locking surface against which said lug normally bears but which surface is adapted to be withdrawn from said lug after said driving shaft has turned a timed distance thereby to release said spring so that it may expand and cause the case to be stripped from the illuminant assembly.

8. The flare of claim 5, said spring seat having a sleeve portion provided with a locking lug, an angularly adjustable setting shaft rotatable within said sleeve and alined with said driving shaft and having a locking lug spaced from said first-named lug, a timing sleeve disposed about said sleeve portion and keyed to said driving shaft to rotate therewith and having a pair of spaced locking surfaces against which said lugs normally bear but which surfaces are adapted to be withdrawn from said lugs after said driving shaft has turned a timed distance thereby to release said spring so that it may expand and cause the case to be stripped from the illuminant assembly.

9. The flare of claim 5, and an axially mounted sleeve within said spring and rotatable with said driving shaft and provided with an arcuate locking surface, an angularly adjustable setting shaft within said sleeve provided with a lug for engaging said locking surface whereby said spring is retained in compression through the engagement of said lug and said locking surface, and means for adjusting said setting shaft to determine the portion of a revolution through which said sleeve must turn with said driving shaft to release said spring and effect disengagement of said case from said illuminant assembly.

10. The flare of claim 5, and a pair of normally interlocked axially alined locking members within said spring for normally maintaining said spring under compression, one of said locking members being rotatable with said driving shaft to release said spring and effect disengagement of said case from said illuminant assembly after said shaft has rotated through a predetermined distance.

11. In an aerial flare of the type wherein a case incloses an illuminant candle and its supporting parachute and is adapted to be stripped therefrom at a predetermined point in the fall of the flare, a spring-operated ignition unit attached to the lower end of the candle, means

controlled by the removal of said case from the parachute and candle for effecting ignition of the candle, and means whereby said ignition unit is released from the candle by the consumption of the illuminant in proximity to said ignition unit.

12. An aerial flare, comprising a case adapted to house an illuminant candle and its supporting parachute, a spring-operated ejecting unit attached to said case for stripping the case from the candle and parachute at a predetermined point in the fall of the flare, a timing unit attached to the lower end of the candle, and means associated with said timing unit for igniting the candle at a predetermined time after the case has been stripped therefrom, said last-named means being released from the candle by the consumption of the ignited illuminant in proximity thereto.

13. An aerial flare comprising a case, an illuminant candle and a supporting parachute detachably mounted within said case, a release

mechanism for stripping the case from the candle and its parachute at a predetermined point in the fall of the flare, and a plurality of fire-resistant shades attached to the candle in longitudinally spaced relation to each other so as to successively drop away from the candle as the candle is progressively consumed.

14. An aerial flare comprising a case, an illuminant candle and a supporting parachute detachably mounted within said case, a release mechanism for stripping the case from the candle and its parachute at a predetermined point in the fall of the flare, and a fire-resistant shade comprising a plurality of separate shade sections 10 15 separately attached to the candle so as to successively drop away therefrom as the candle is progressively consumed, each shade section comprising an annular portion sleeved about the candle and an annular flange extending downwardly therefrom at an angle thereto.

JOHN F. CAVANAGH.
